MINING MACHINE HAVING ADJUSTABLE ROTARY CUTTER HEADS ON ROTARY TURRETS

Jerry Karlovsky, Jr., Nashville, and Richard A. Butler, Carlyle, Ill., assignors to National Mine Service Company, Pittsburgh, Pa., a corporation of West Virginia

Filed Dec. 2, 1966, Ser. No. 598,858
26 Claims. (Cl. 299—57)

This application is a continuation-in-part of copending application Ser. No. 370,193 entitled, "Mining Machine Having Adjustable Rotary Cutter Heads on Rotary Turrets," filed on May 26, 1964, and now abandoned.

This invention relates to a continuous mining machine and more particularly to a boring type continuous mining machine that has a plurality of rotatable turrets and a plurality of rotatable cutter heads positioned on each of the rotatable turrets.

Recently a drilling head has been developed that can drive large diameter entries or bores into hard material such as iron ore or the like at a much faster rate than other known conventional boring machines. The drilling head has a cylindrical body portion and a conical front end portion. A plurality of rotatable plates with picks or cutting devices extending therefrom are secured to the conical front end portion in lateral spaced relation to the longitudinal axis of the cylindrical body portion. The axis of each rotatable plate is inclined relative to projected planes that include the longitudinal axis of the cylindrical body portion and the axis of each rotatable plate also diverges angularly away from the longitudinal axis of the cylindrical body portion. Drive means are provided to rotate the head about the longitudinal axis of the cylindrical body portion and to rotate the angularly positioned plates about their respective axes. The plates, therefore, revolve about the longitudinal axis of the body portion as the body portion rotates and rotate about their individual axes. The drilling head is described in U.S. Patent Re. 25,470 entitled "Drilling Head for Sinking Shafts, Galleries or the Like."

It is believed that the rapidity of dislodging the hard materials is attributable to the manner in which the cutting devices secured to the front or top face of the rotatable plates contact or strike the material to be dislodged. The picks have their cutting edges facing toward the direction of rotation of the plates and the plates are so positioned that the picks on each plate strike one after the other into the material to be dislodged and then are immediately withdrawn. The rotation of the cylindrical body portion in conjunction with the rotation of the rotary plates provides a drilling head where the rotary plates are continuously revolving about the axis of the body portion and the picks or cutting devices are continuously dislodging the material in parallel elongated arcuate paths that intersect the circular path circumscribed by the rotary plates as they revolve about the longitudinal axis of the cylindrical body portion.

The drilling head has a fixed diameter body portion with an Archimedean screw portion thereon to convey the cuttings dislodge by the rotary plates at the front end of the drilling head rearwardly to a suitable receiver. The cylindrical body portion of fixed diameter limits the diameter of the bore or entry that can be made with the drilling head and the Archimedean screw portion limits the amount of material that can be conveyed rearwardly through the bore to the receiver.

The continuous mining machine hereinafter described includes a plurality of rotatable boring heads or turrets that have a plurality of rotatable cutter heads positioned thereon in spaced lateral relation to the longitudinal axis

of the respective turret. The cutter heads are positioned on the front end of the turrets in a preselected angular relation to the axis of the turret. Certain of the cutter heads are adjustable laterally relative to the axis of the turret so that the effective diameter of the turrets may be rapidly changed and the continuous mining machine can dislodge material from seams of different thickness.

Briefly, the invention includes a mining machine having a plurality of rotatable turrets extending forwardly therefrom. The turrets include a pilot drill and a plurality of rotatable cutter heads having picks or cutting devices extending forwardly therefrom. Certain of the rotatable cutter heads are radially adjustable relative to the longitudinal axis of the rotatable turrets to increase or decrease the diameters of the bores formed in the material by the mining machine so that the continuous mining machine can be used to remove material from seams having different thicknesses and can be easily maneuvered in the haulageways or entries of a mine. An adjusting means is provided to adjust the relative position of the adjustable cutter heads. The rotatable cutter heads are secured to the rotatable turrets in a manner that the front face of each of the cutter heads is at an angle with a plane perpendicular to the longitudinal axis of the turrets. The axis of the cutter heads is inclined relative to planes comprising the longitudinal axis of the rotatable turrets. The rotatable cutter heads, therefore, have a compound angular relation relative to the longitudinal axis of the rotatable turrets so that the cutting edges of the picks or cutting devices secured to the front portion of the cutter heads face in the general direction of rotation of the cutter heads, and less than all the picks or cutting devices on each rotatable head contact the material to be dislodged at the same time. The longitudinal axes of the cutter heads are not parallel to the longitudinal axes of the rotary turrets. The longitudinal axes deviate outwardly at a slight angle relative to a plane parallel to the longitudinal axis of the turret so that less than all of the picks or cutting devices are in contact with the material to be dislodged at any one time, and the longitudinal axes of the rotatable cutter heads further deviate angularly toward the direction of rotation of the respective turret so that the cutting edges of the picks or cutting devices face toward the direction of rotation of the rotatable cutting heads.

The adjustment means for adjusting certain of the rotatable cutter heads includes a means to maintain the same angular relation between the axis of the adjustable cutter heads and the longitudinal axis of the rotatable turrets in various positions of radial adjustment.

Accordingly, the principal object of this invention is to provide a continuous mining machine having a plurality of rotatable turrets extending forwardly therefrom with radially displaced rotatable cutter heads thereon that are radially adjustable relative to the longitudinal axis of the rotatable turrets.

Another object of this invention is to provide a rotatable turret for a continuous mining machine with a plurality of rotatable cutter heads adjustably positioned thereon in angular relation to the longitudinal axis of the turret and certain of the cutter heads being adjustable radially on the turret.

A further object of this invention is to provide a rotatable turret for a continuous mining machine that has a rotatable cutting head extending forwardly therefrom and adjustable radially relative thereto.

Another object of this invention is to provide an adjustment means for maintaining a preselected angular relation between a radially adjustable rotatable cutter head extending forwardly from a rotatable turret.

These and other objects and advantages of this invention will be more completely disclosed and described in the following specification, the accompanying drawings and the appended claims.

In the drawings:

FIGURE 13 is a view in side elevation of another embodiment of the continuous mining machine wherein the turrets have a center pilot drill, an intermediate cutter head and a pair of outer cutter heads.

FIGURE 14 is a top plan view of the front portion of the mining machine illustrated in FIGURE 13.

FIGURE 15 is a semi-diagrammatic view in front elevation of the mining machine illustrated in FIGURES 13 and 14 and illustrating the pairs of outer cutter heads in various adjusted positions.

FIGURE 16 is a developed section taken along the line 16—16 in FIGURE 14 and illustrating the drive and adjustment mechanism for one of the outer cutter heads.

FIGURES 17, 18, 19 and 20 are views in section and in front elevation, taken along the lines 17—17, 18—18, 19—19 and 20—20 respectively in FIGURE 16, and illustrating a portion of the gearing for adjusting and driving the outer cutter head.

FIGURE 21 is a schematic perspective of the lock assembly and adjusting gear train illustrated in FIGURE 16.

FIGURE 22 is a diagrammatic illustration of the adjustment gear train and mechanical lock assembly.

FIGURE 23 is a diagrammatic illustration of a gear drive for the pair of outer cutter heads and is similar to the schematic diagram illustrated in FIGURE 12.

FIGURE 24 is a view partially in section similar to FIGURE 4 illustrating another embodiment of the drive means for the outer and intermediate cutter heads and the pilot drill.

FIGURE 25 is a view in front elevation of one of the cutter heads with the cutting bits removed.

FIGURE 26 is a view in section of the cutter head taken along the line 26—26 in FIGURE 25 and including cutter bits positioned in the respective bit receivers.

General description

Referring to the drawings and particularly FIGURES 1—3, the continuous mining machine generally designated by the numeral 10 has a body or main frame 12 with a trough-shaped conveyor compartment 14 extending longitudinally thereof. The conveyor compartment 14 has a front opening or throat 16, as illustrated in FIGURE 3. A conveying means, such as an endless chain conveyor, extends along the bottom of the compartment 14 and conveys material dislodged by the rotary turrets 18, 20, 22 and 24 rearwardly along the compartment 14. A pivoted end section 26 is provided for the conveyor that is pivotally adjusted by swing cylinders 28 and 30 to discharge the dislodged material onto suitable conveying means, such as shuttle cars or the like, stationed at the rear of the mining machine 10. The body 12 is mounted on endless tracks 32 and 34 that propel or tram the mining machine 10 in a preselected direction. A suitable hydraulic pump drive motor generally designated by the numeral 36 which, through suitable gearing, drives the hydraulic pumps 37, provides the traction drive for the mining machine 10. Adjacent one side of the body 12 there is an operator's compartment 38 with suitable control levers 40 for controlling the various functions of the mining machine.

The front end of the body 12 has an elongated rectangular transmission housing 42 in which the main timing gear train is housed. A pair of electric motors 44 and 46 are connected to the transmission housing 42 and are suitably supported thereby. Each of the motors 44 and 46 has a clutch housing 48 positioned between the respective motor and the transmission housing 42. Centrifugal mechanisms within the clutch housing 48 are arranged to drivingly connect the motors 44 and 46 to the gearing within the transmission housing 42.

There is also provided an endless trimmer chain 50 that is supported by a pair of horizontal bars 52 and 54 adjacent the roof and floor of the entry. Pairs of cylinders 56 are arranged to extend and retract the bar 52 and pairs of cylinders 58 are likewise arranged to extend and

retract the bar 54 and thereby adjust the relative horizontal position of the trimmer chain 50. The trimmer chain 50 is arranged to remove the kerfs of material between the circular bores formed by the turrets 18, 20, 22 and 24. It should be understood that other means may be provided

to remove the kerfs of material left by the rotary turrets, such as drum type trimmer bars and the like.

Referring to FIGURE 5, the main transmission housing 42 has a pair of rearwardly extending portions 60 and 62 that contain gears for reducing the angular velocity of the timing gear train 104 housed in the transmission housing 42. Extending forwardly from the main transmission housing 42 are four auxiliary housings 64, 66, 68 and 70 which rotatably support the respective rotary turrets 18, 20, 22 and 24 (FIGURE 3).

The rotary turrets

The turrets 18, 20, 22 and 24 are of substantially the same construction and include a body portion 72 with a rear portion 74 secured thereto. The rear portion 74 has a cylindrical end portion 76 which rotatably extends into

and is supported in the respective auxiliary housing and the main transmission housing 42. FIGURE 5 illustrates the cylindrical end portion 76 of turret 24 rotatably supported in the main transmission housing 42 and the forwardly extending housing 70. Bearings 78 rotatably support the end portion 76 of rotary turret 24 in housing 70.

The turret body portion 72 illustrated in FIGURE 4 has a generally cylindrical support 80 extending forwardly and angularly therefrom. An intermediate cutter head 82 is rotatably supported on the front end portion of the cylindrical support 80. The support 80 is so shaped that the front surface of the intermediate cutter head 82 is angularly displaced relative to the longitudinal axis of the rotary turret 18. Also extending forwardly from the front end of the turret body portion 72 is a pilot drill support 84 that is aligned with the longitudinal axis of the respective rotary turret. Extending forwardly from the drill support 84 is a center pilot drill 86 which is axially aligned with the longitudinal axis of the respective rotary turret (see FIGURE 4).

Rotatably supported by and extending forwardly from an intermediate surface 88 of the turret body portion 72 is an inner turntable 90. The turntable 90 is rotatable relative to the body portion 72 about an axis 92 which is parallel to the longitudinal axis 94 of the rotary turret. Connected to the inner turntable 90 is an outer turntable 96 which is rotatable relative to the inner turntable 90 about an axis 98 which is parallel to and displaced laterally from the axis 92 about which the inner turntable 90 rotates relative to the body portion 72. The rotation of outer turntable 96 relative to turntable 90 revolves the axis 98 of turntable 96 about the axis 92 of the inner turntable. Extending forwardly from the outer turntable 96 is a housing 100 on the front end of which is rotatably supported an outer cutter head 102. The surface of the cutter head 102 is angularly arranged relative to the longitudinal axis 94 of the rotary turret 72. Because of the configuration of the inner turntable 90 and the relative position of the outer turntable 96 thereon the rotation of inner turntable 90 about axis 92 revolves the axis 98 of the outer turntable 96 about the axis 92 to move the outer cutter head 102 radially toward and away from the center pilot bit 86. The relative angularity of the front surface of the cutter head 102 can be changed by rotating the outer turntable 96 about the axis 98. With this construction the radial dimension of the turret and the angularity of the cutter head 102 can be readily and rapidly adjusted.

Referring to FIGURE 3, the outer cutter head 102 determines the radius of the bore made by the respective rotary turrets in the material being dislodged. By the arrangement of the double turntables 90 and 96 it is possible to extend or retract the outer cutter head 102 to change the respective effective radial dimension of the rotary turret. For example, viewing FIGURE 4, when the inner turret 90 is rotated about the axis 92, the outer cutter head 102 moves toward the pilot drill 86 to reduce the overall radial dimension of the rotary turret. After the adjustment of the radial dimension by rotation of inner turntable 90 about axis 92, the desired angular relationship of the outer cutter head 102 to the rotary turret can be obtained by rotating the outer turntable 96 about the axis 98. The relative radial dimensions of the turrets 18, 20, 22 and 24 can thereby be adjusted to provide a maximum and minimum cutting height for the mining machine. As will be later discussed, where it is desired to reduce the radial dimension of the turrets to tram the mining machine through the haulageways, the radial dimension of the respective rotary turret is reduced by rotating the turntable 90 about the axis 92. If the turrets are going to again be used at the same radial dimension as before, it is not necessary to then adjust the angularity of the outer cutter head by the rotation of the outer turntable 96 relative to the inner turntable 90. As will be later described, a power driven adjustment means is provided

for rotating the turntable 90 about axis 92 relative to the turret body portion 72. A manual adjustment means is provided to rotate the outer turntable 96 relative to the inner turntable 90 and thereby adjust the relative angularity of the outer cutter head 102.

Turret drive arrangement

The rotary turrets 18, 20, 22 and 24 are rotatably driven in timed relation by the motors 44 and 46 through gearing in the main transmission housing 42. The motors 44 and 46 also rotate the respective center pilot drill 86, intermediate cutter head 82, and outer cutter head 102 on each of the respective turrets 18, 20, 22 and 24 through gearing in the main transmission 42 and gearing in the turret body portions 72. As will be apparent from FIGURE 3, pairs of turrets rotate in the same direction. For example, rotary turrets 18 and 20 rotate in a counterclockwise direction and the cutter heads are angularly displaced from each other. The rotary turrets 22 and 24 rotate in a clockwise direction and are also angularly displaced from each other. The rotation of turrets 18 and 20 in a counterclockwise direction serves to move the material dislodged by the cutter heads laterally toward the conveyor throat 16. Similarly, the clockwise rotation of turrets 22 and 24 conveys the material dislodged by the cutter heads on the respective turrets 22 and 24 toward the conveyor throat 16. The housing 74 of each of the turrets has a plurality of spiral plows or paddles extending radially therefrom to assist in conveying the dislodged material toward the conveyor throat 16. The plows generally designated by the numerals 332 and 334 on turrets 18 and 24 are arranged to push the dislodged material forwardly to keep the material from accumulating along the corners of the rib or side wall where the dislodged material frequently interferes with the operation of the trim chain 50. The flat portions of the turret housings 72 and 90 on turrets 18 and 24 will urge the dislodged material toward the center portion of the machine 10. The plows 336 and 338 on turrets 20 and 22 are so shaped that they urge the material rearwardly toward the conveyor throat 16.

On the rotary turrets 18 and 20 the pilot or center drills 86 rotate in the same counterclockwise direction as the turrets 18 and 20. The intermediate and outer cutter heads 82 and 102 rotate in a clockwise direction relative to the counterclockwise rotating turrets 18 and 20. The pilot drills 86 on turrets 22 and 24 rotate in a counterclockwise direction relative to the clockwise rotating turrets 22 and 24. The intermediate and outer cutter heads 82 and 102 rotate in a counterclockwise direction on the clockwise rotating turrets 22 and 24.

Drive and gearing

The gearing arrangement for driving the respective turrets 18, 20, 22 and 24 and the intermediate and outer cutter heads 82 and 102 and the central pilot drills 86 on each of the respective cutter heads is illustrated diagrammatically in FIGURE 12. The motors 44 and 46 are connected through gearing to the interconnected main gear train generally designated by the numeral 104. The motor 44 has shaft 106 with a gear 108 secured thereto that meshes with a gear 110. A common shaft 112 has gear 110 and gear 114 secured thereto for rotation therewith. A gear 116 meshes with gear 114 and transmits rotation through shaft 118 to a gear 120 on the end of interconnected main gear train 104.

Similarly, the motor 46 drives a gear 122 through shaft 124. Gear 126 meshes with gear 122 and transmits rotation through shaft 128 to gear 130. A shaft 132 has a gear 134 connected thereto which meshes with gear 130. The shaft 132 has a gear 136 connected thereto for rotation therewith so that rotation of the motor 46 is transmitted through the gearing 122, 126, 130 and 134 to gear 136 on the end of interconnected main gear train 104. FIGURE 5 illustrates the drive arrangement from the mo-

tor 46 to the main gear train 104. The motors 44 and 46 rotate in opposite directions and, through the last mentioned gearing, both drive the interconnected gearing in main gear train 104.

Referring again to FIGURE 12, the main gear train 104 has a gear 138 meshing with gear 120. A main drive shaft 140 for the intermediate and outer cutter heads 82 and 102 and the center pilot drill 86 of turret 18 is driven by gear 138. Similarly, a main shaft 142 drives the intermediate cutter heads, outer cutter head, and center pilot drill of turret 20, and is connected to and driven by a gear 144 in the main gear train 104. Gears 138 and 144 in main gear train 104 are interconnected by meshing gears 146, 148 and 150 so that both gears 138 and 144 rotate in the same counterclockwise direction. The gear 148 also rotates in a counterclockwise direction and is connected through a shaft 152 to a gear 154 in the turret drive transmission for the left hand turrets 18 and 20, as viewed in FIGURE 12. The turrets 18 and 20 have gears 156 and 158 associated therewith and nonrotatably secured to the turret housing end portion 76 so that rotation of the respective gears 156 and 158 rotates the turrets 18 and 20. The gears 156 and 158 through reach gears 160 and 162 mesh with gear 154 so that shaft 152 drives both turrets 18 and 20 in a counterclockwise direction.

A main drive shaft 164 arranged to rotate the intermediate and outer cutter heads and the center pilot drill on the turret 22 is connected to a gear 166 in the main gear train 104. Similarly, a main drive shaft 168 to drive the intermediate and outer cutter heads and the center drill on turret 24 is connected to a gear 170. The gear 170 meshes with drive gear 136 in main gear train 104 and is connected to gear 166 through meshing intermediate gears 172, 174 and 176 so that gears 170 and 166 are both driven in a clockwise direction by the motors 44 and 46. Connecting gears 178, 180, 182 and 184 are arranged in meshing relation and connect the gears 166 and 144 so that main gear train 104 is a constantly meshing gear train arranged to rotate the turrets in timed relation to each other and in a preselected angular relation to each other. The gear 182 has a trimmer chain drive shaft 183 connected thereto and rotatable therewith. The drive shaft 183 has a drive gear 185 connected thereto that meshes with the trimmer chain 50 so that trimmer chain 50 is also driven by the main gear train 104.

The turret 22 similarly has a gear 186 associated therewith that is driven in a clockwise direction by means of gears 188 and 190. The turret 24 has a gear 192 associated therewith that is driven by gear 190 through reach gear 194 and gear 174 of the main gear train 104 drives gear 190 through shaft 196. With this arrangement the turrets 22 and 24 are driven in a clockwise direction by the gear train 104. The gearing from motor 46 to turret 24 and shaft 168 is illustrated in FIGURE 5.

The gear trains for driving the intermediate cutter head and the outer cutter heads are substantially the same in all of the turrets 18, 20, 22 and 24 and only the gearing associated with turret 24 will be described in detail. In FIGURE 12 there is schematically illustrated an extension of shaft 168 that has a gear 198 connected thereto for rotation therewith. FIGURE 4 illustrates in detail the gear train within the turret 24 for driving the center pilot drill 86, the intermediate cutter head 82 and the outer cutter head 102. The gear 198 provides a common drive for the intermediate and outer cutter heads and the center pilot drill, as is shown in FIGURE 6. A pair of reach gears 200 and 202 mesh with the gear 198 and drive a gear 204 that is nonrotatably connected to intermediate cutter head drive shaft 206. The cutter head 82 is nonrotatably connected to the drive shaft 206 by the coupling illustrated in FIGURE 4 that will be later described. Thus, the clockwise rotation of main drive shaft 168 transmits counterclockwise rotation to the intermediate cutter head

82 on the turret 24 through shaft 206. FIGURE 6 illustrates the arrangement of the gears 198, 200, 202 and 204 that rotate shaft 206. The outer cutter head 102 on turret 24 is also rotated in a counterclockwise direction by means of gears 208, 210, and 212. Gear 212 is nonrotatably connected to a drive shaft 214 and the drive shaft 214 extends into the inner turntable 90 and has a gear 216 connected to its end portion within turntable 90. Final drive shaft 218 connected to the outer cutter head 102 has a gear 220 connected thereto within the inner turntable 90. An intermediate gear 222 connects the gears 216 and 220 to rotate the final drive shaft 218 and outer cutter head 102 in a counterclockwise direction.

The center cutter bit 86 on turret 24 is driven by the intermediate cutter head drive shaft 206. Within the turret body portion 72 the intermediate cutter head drive shaft 206 has a gear 224 connected thereto and rotatable therewith. A shaft 226 has a gear 228 that meshes with gear 224 on the intermediate cutter head drive shaft 206. The shaft 226 has another gear 230 thereon that meshes with a gear 232 connected to the center pilot drill drive shaft 234. The center pilot drill drive shaft 234 is connected to the center pilot drill 86 so that rotation of gear 232 rotates the center pilot drill 86. With this arrangement the main drive shaft 168 rotates the center pilot drill 86 in a counterclockwise direction through the gearing and shafting previously described.

It should be noted that the center pilot drills 86 on the turrets 18 and 20 also rotate in a counterclockwise direction. Within the housing 72 of turrets 18 and 20 there is, as illustrated in FIGURE 7, an intermediate drive shaft 206 that has a gear 224 connected thereto. The shaft 226 has a gear 228 connected thereto that meshes with gear 224 and is driven thereby. Another shaft 236 has a pair of gears 238 and 240 axially positioned thereon and rotatable therewith. The gear 228 on shaft 226 meshes with gear 238 to drive shaft 236. Gear 240 meshes with a gear similar to gear 232 on the center pilot drill drive shaft 234. With the additional shaft 236 and the gears 238 and 240, the center pilot drills 86 on the turrets 18 and 20 are arranged to rotate in the same counterclockwise direction as the center pilot drills 86 on turrets 22 and 24.

The above described gearing is so proportioned that the center pilot drills 86, intermediate cutter heads 82 and outer cutter heads 102 rotate at a greater angular velocity or speed than the turrets 18, 20, 22 and 24.

Outer cutter head adjustment mechanism

Referring now to the adjustment mechanism for the turntable 90, there is illustrated in FIGURES 5 and 8 the drive shaft 168 having the previously described drive gear 198 thereon coaxially positioned on the drive shaft 168 and rotatable relative thereto is a tubular shaft 242 which is also illustrated in its entirety in FIGURE 5. The tubular shaft 242 has a gear 244 nonrotatably positioned thereon within the main transmission housing 42. The gear 244 is axially movable on the tubular shaft 242 and is arranged to mesh with an internally toothed geared portion 246 that forms a part of the turret rear portion 76. Thus, when the gear 244 is meshed with the internally toothed gear portion 246, the tubular shaft 242 rotates at the same rate as the turret 24 and the inner turntable 90 is in a locked fixed position relative to the turret 24.

As illustrated in FIGURE 10 a shift lever 266 is connected to the gear 244 at 248 to move the gear 244 axially on shaft 242 into and out of engagement with the internally toothed portion 246 on turret rear end portion 76. A piston cylinder actuator 268 is provided and suitably secured to the portion of the main transmission housing 42 to move the shift lever 266 and thereby engage or disengage gears 244 and 246. The shift lever 266 is further utilized to move the gear 244 into engagement with the gear 250. Diagrammatically illustrated in FIGURE 9 the gear 244 is illustrated as meshing with the gear 250. A

suitable servomechanism 254 has a shaft 252 extending forwardly therefrom that has gear 250 rotatably secured thereto. The servomechanism 254 may be a hydraulic motor or the like. Suitable control means are provided for the piston cylinder 268 and the servomechanism or hydraulic motor 254 so that the gear 244 may be moved axially on shaft 242 out of engagement with the internally toothed gear 246 and into meshing relation with gear 250. The control means further actuates the hydraulic motor 254 to thereby rotate gear 244 and through the gear train to be described rotates the inner turntable 90 about the axis 92 (FIGURE 4).

Within the rear turret housing portion 74 the tubular shaft 242 has a gear 256 nonrotatably secured thereto, as shown in FIGURE 8. The gear 256 meshes with a gear 258 nonrotatably secured to shaft 260. The rear portion of the primary turntable 90 that extends into the turret housing 72 has an externally toothed gear 262 secured thereto. The gear 262 meshes with a gear 264 secured to the end of shaft 260 within the turret housing 72 (FIGURE 8). With this arrangement the primary turntable 90 can be rotated about the axis 92 relative to the housing 72 by disengaging gear 244 from the internally toothed portion 246 of the turret housing portion 72 and engaging gear 244 to gear 250 associated with the servomechanism 254. Actuation of the servomechanism 254 drives the gears 250, 244, 256, 258 and 264 to rotate the primary turntable 90 through the gear 262 about the axis 92 to thus move the outer cutter 102 relative to the longitudinal axis 94 of the turret 24. All of the turrets 18, 20, 22 and 24 have a similar adjusting means for the inner or primary turntable 90. The shift mechanisms may be suitably interconnected so that the operator moves all shift levers 266 at the time to either engage or disengage the gears 244 and 246. Similarly, the servomechanisms 254 for the respective turret heads 18, 20, 22 and 24 may be interconnected through a suitable control means so that the outer cutter heads 102 on all of the turrets 18, 20, 22, and 24 may retract or extend the same amount.

Referring to FIGURES 4 and 11 the outer turntable 96 may be adjusted relative to the inner turntable 90 by rotating the outer turntable 96 about the axis 98. The inner turntable 90 has an arcuate forwardly extending portion 270 in which there are formed a plurality of radially extending slots 272. The outer turntable 96 has a laterally extending portion 274 with a radial slot 276 therein. The outer turntable 96 is so constructed that upon rotation about the axis 98 the slot 276 in outer turntable 96 is in overlying relation with the arcuate portion 270 of inner turntable 90. The outer turntable 96 has a longitudinal threaded bore 278 therein. A wedge 280 having a longitudinal bore 282 therein is positioned in the slot 276 of the outer turntable 96 and in an aligned slot 272 in the arcuate portion 270 of inner turntable 90. A bolt 284 extends through the bore 282 in wedge 280 and is threadedly secured in bore 278 in outer turntable 96. With this arrangement the wedge 280 is fixedly secured in aligned slots 276 and 272 to maintain the outer turntable 96 in fixed relation to the inner turntable 90.

To adjust the outer turntable 96 relative to the inner turntable 90 the wedge 280 is removed from the aligned slots 276 and 272 and the outer turntable 96 is rotated about the axis 98 relative to inner turntable 90 until the desired angular relationship of the outer cutter head 102 is attained. The wedge 280 is then again positioned in the aligned slots 272 and 276 and secured in the respective slots by the bolt 284 to again fixedly secure the outer turntable 96 relative to the inner turntable 90. With this arrangement the relative angularity of the outer cutter head 102 may be adjusted relative to the longitudinal axis of the turret to provide the optimum angle for the outer cutter head 102.

It will be apparent that the specific configuration of the turrets may be modified without departing from the invention herein disclosed. For a better understanding of

the manner in which the turret is fabricated and assembled, a general description of the turret housing configuration and the structure for supporting the shafts and gears will be generally described. It will be apparent that modifications to this specific configuration can be made without departing from the invention.

Referring to FIGURE 4 the turret body portion 72 has a side wall 286 which forms a cavity 288 in which the gearing and shafting for driving the intermediate cutter head 82 and the center pilot bit 86 are housed. The body portion 72 has a front end portion 290 to which there is secured a plate 292. The cylindrical support 80 for the intermediate cutter head 82 is secured to the plate 292 and extends forwardly therefrom. The cylindrical support 80 has a cavity 294 in which the rotary portion of the intermediate cutter head 82 is connected to the drive shaft 206 by means of a universal coupling 296 such as a Rezeppa joint or the like. Also secured to and extending forwardly from the plate 292 is the cylindrical pilot drill support 84. The pilot drill support 84 rotatably supports an intermediate portion of shaft 234.

There is provided within the cavity 288 of the turret body portion 72 an intermediate wall 298 which provides supports for end portions of shafts 234, 226 and 206. The turret body portion 72 has a rear wall 300 with apertures therethrough for the shafts 206, 168 and 214. Suitable bearing supports are provided in the rear wall 300 for the end portion of shaft 168. The turret body portion 72 has a cylindrical portion designated by the numeral 302 positioned adjacent to the main body portion which provides a support for the inner turntable 90. The cylindrical portion 302 has a front intermediate annular face 88 and has an internal cavity 304 that receives a portion of the inner turntable 90. The inner turntable 90 has a rearwardly extending cylindrical portion 306 that has an axial bore 308 therethrough. The cylindrical portion 306 is supported within the cavity 304 by means of suitable bearings to permit the turntable rear portion 306 to rotate within the cavity 304 about the axis 92. Secured to the rear face of the inner turntable rear portion 306 is the gear 262 that meshes with the gear 264, as illustrated in FIGURE 8. The inner turntable 90 has a laterally extending front portion 310 that serves as a housing for the gearing drivingly connecting shafts 214 and 218. The housing 310 extends laterally from the rear portion 306 so that rotation of the inner turntable 90 about the axis 92 will revolve the laterally extending portion of housing 310 about the axis 92. Suitable means are provided to secure the inner turntable 90 to the turret body portion 72, such as the bolts 312. As illustrated in FIGURE 11, the housing front end portion has an arcuate forwardly extending portion 270 with radially extending slots 272 that serve to fixedly position the outer turntable 96 relative to the inner turntable 90, as has been previously described.

The outer turntable 96 has a rear portion 314 with the laterally extending portion 274. The housing that supports the outer cutter head 102 is secured to the outer turntable rear end portion 314. The outer turntable rear portion 314 has suitable bearings to support the outer cutter head drive shaft 218. Within the housing 100 connected to the front portion of outer turntable rear portion 314 there is a Rezeppa type universal joint 316 connected to shaft 218. Extending forwardly from the Rezeppa joint 316 is an end shaft 318 that is drivingly connected to the rotatable portion of the outer cutter head 102. The fixed nonrotatable portion of outer cutter head 102 extends into the housing 100 and is suitably supported and secured therein. The shaft 218 defines an axis 98 and the housing 100 is so shaped that the end shaft 318 defines a second axis 322 that is angularly displaced from the axis 98. The shape of housing 100 maintains the outwardly diverging axis 322 fixed relative to axis 98.

As is clearly illustrated in FIGURES 1, 2 and 3 the housings 80 and 100 are so shaped that the cutter heads are also inclined in the direction of rotation of the turrets. Thus the front portion of both the intermediate cutter head 82 and outer cutter head 102 diverge or are at an angle to a longitudinal axis of the turret indicated by the numeral 94 and are inclined in the direction of rotation. This compound angular arrangement is referred to as the angular relation of the cutter heads to the longitudinal axis 94 of the turret. A suitable angular relation has been found to be an 8° diverging angle and a 17° angle of inclination in the direction of rotation.

The rotation of turntable 96 about the axis 98 changes the angular relation of the outer cutter head 102 to the axis 94. Similarly, rotation of turntable 90 about axis 92 changes the angular relation of the outer cutter head 102 to the axis 94. Where, however, the two turntables 90 and 96 are rotated in opposite direction through equal angles, the angular relation remains the same and the outer cutter head moves toward or away from the longitudinal axis 94.

Outer cutter head 102 and intermediate cutter head 82 have a front portion 324 with an annular beveled surface 326 on which there is positioned a plurality of cutter bits 328 that have their cutting surfaces facing the direction of rotation of the respective cutter heads.

The turret body portion 72 has a rear wall 300 to which is connected a rear portion previously generally designated by the numeral 74 which forms a transmission housing for the gearing that connects the main drive shaft 168 to the drive shafts 214 and 206. The turret rear portion 74 has a cylindrical portion 76 nonrotatably secured thereto means of the annular lip 330 on the housing rear portion 74. The cylindrical portion 76 extends into and is rotatably supported by the auxiliary housing 70 secured to the main transmission housing 42.

There is illustrated in FIGURE 24 a turret assembly generally designated by the numeral 600 that has a modified drive arrangement for the intermediate cutter head 602, the pilot drill 604 and the outer cutter head 606. The turret assembly has a main housing 608 with a forwardly extending support 610 for the intermediate cutter head 602. Rotatably supported and extending forwardly from the housing 608 is an inner turntable 612 that is rotatable relative to the housing 608 about an axis 614. Upon rotation of turntable 612 about the axis 614 the outer cutter head 606 moves toward and away from the intermediate cutter head 602. Connected to the inner turntable 612 is an outer turntable 616 that is rotatable relative to the inner turntable 612 about an axis 618. The axis 618 is parallel to and displaced laterally from the axis 614. The outer turntable 616 is secured to the inner turntable 612 by bolts 620 arranged in a circular configuration so that the outer turntable 616 may be rotated relative to inner turntable 612 by removing the bolts 620 and repositioning the outer turntable 616 and aligning the bolt holes to obtain the desired angularity of the outer cutter head 606. The inner turntable 612 is rotated relative to the housing 608 with the mechanism illustrated in FIGURE 8 and previously described. The inner turntable has an externally toothed gear portion 622 that is similar to the gear 262 illustrated in FIGURE 8 and upon rotation of the externally geared portion 622 the inner turntable 612 rotates about the axis 614.

The manner in which the inner and outer turntables 612 and 616 are adjusted is substantially the same as the embodiment illustrated in FIGURE 4 with the exception of the circular configuration of bolt holes in the front face of the inner turntable 612 and the mating circular configuration of bolt holes in the outer turntable 616. Adjustment or rotation of outer turntable 616 is accomplished by removing the bolts and rotating the outer turntable 616 relative to the inner turntable 612 about the axis 618.

The turret 600 has a cylindrical end portion 624 supported in the main transmission housing with drive gear 626 splined thereto. Within the cylindrical end portion 624 there is positioned a tubular shaft 628 that has a gear 630 secured thereto and extending into the housing 608. The gear 630 is drivingly connected by means of a pair of gears and a shaft (not shown) to the externally geared portion 622 of inner turntable 612. Thus by rotating the cylindrical shaft 628 the inner turntable 612 is rotated about the axis 614 to adjust the relative position of outer cutter head 606.

Positioned within the tubular shaft 628 is a drive shaft 632 for the cutter heads 602 and 606 and the pilot drill 604. The shaft 632 is driven in the same manner as shaft 168 illustrated in FIGURES 4 and 5. A gear 634 is secured to the shaft 632 and meshes with gear 636 connected to shaft 638. Shaft 638 is in turn directly connected through the universal joint 640 to the intermediate cutter head 602. Thus rotation for intermediate cutter head 602 is provided from input shaft 632 through gears 634 and 636 and shaft 638.

Shaft 638 has a gear 642 secured thereto and rotatable therewith that meshes with an intermediate gear 644 supported on a suitable shaft (not shown) to drive gear 646 connected to shaft 648 that is in turn directly connected to the pilot bit 604. With this arrangement, drive for the pilot bit 604 is provided from shaft 632 through gears 634 and 636, shaft 638, gears 642, 644, 646 and shaft 648.

The drive for outer cutter head 606 is provided by means of a shaft 650 that has a gear 652 connected to its end portion. An idler gear 654 suitably supported on an idler shaft (not shown) drivingly connects gear 634 to gear 652 to thus provide rotation to shaft 650 in the same direction as drive shaft 632. The idler gear 654 is in the same plane as gears 634 and 652 and may be located above or below the pair of gears 634 and 652. The shaft 650 is suitably supported in the housing 608 and turntables 612 and 616 and has a gear 656 connected thereto within the inner turntable 612. A shaft 658 is secured to the outer cutter head 606 and has a gear 660 secured thereto that meshes with gear 656. With this arrangement, drive is provided from input shaft 632 to the outer cutter head 606 through gears 634, 654, 652, shaft 650 and meshing gears 656 and 660 to thus rotate shaft 658 and outer cutter head 606 in the opposite direction to the direction of rotation of shaft 632 and in the same direction of rotation as inner cutter head 602.

The configuration illustrated in FIGURE 24 reduces the number of shafts and gears required to rotate the cutter heads 602 and 606 from input shaft 632. With this arrangement, it is possible to increase the size or strengthen the drive gears without increasing appreciably the size of the housing. Although only two modifications of the drive arrangement for the inner and outer cutter heads is illustrated, it should be understood that other drive arrangements are possible without departing from the invention herein described.

It will be apparent with the previously described mining machine that the outer cutter heads may be readily adjusted to increase or decrease the effective diameter of the bores made with the respective turrets. The outer cutter heads are also adjustable so that the desired angular relation between the outer cutter heads and the axis of the turret can be obtained at any of the adjusted positions. With this arrangement the mining machine herein described has the advantageous features of the recently developed drilling head and, further, is versatile in that the machine can be used to mine seams of different thickness. The ability to retract the outer cutter head provides desired maneuverability for the machine. The remote controlled adjustment permits rapid retraction of the outer cutter heads so that the machine can be quickly withdrawn from an area where a roof fall is imminent.

Drive for the pair of outer cutter heads

Referring to FIGURES 13, 14 and 15, the mining machine generally indicated by the numeral 400 is similar in many respects to the mining machine 10 previously described and the same elements will be indicated by the same numerals. The main drive gear train within the main transmission housing 42 is substantially the same as main gear train 104. The drive mechanism for the intermediate cutter heads 82 and the center pilot drills 86 for the turrets 402, 404, 406 and 408 may be the same as either embodiment previously described and will not again be described.

Referring to FIGURES 23 and 16, the pairs of outer cutter heads 410 and 412 on end turret 408 are driven by the drive shaft 168 connected at its rear end portion by gear 170 to the common gear train 104. The shaft 168 has secured to its other end portion gear 198 which meshes with and drives gears 414 and 416 on opposite sides thereof. Gear 414 meshes with gear 417 that, in turn, meshes with gear 418. The gear 418 is nonrotatably connected to one end of shaft 420 so that shaft 420 is driven by shaft 168 through the gear train 198, 414, 417 and 418. Connected to the other end of shaft 420 is a gear 422 that meshes with a gear 424 connected to the end of a shaft 426. The shaft 426 has a gear 428 secured to its end portion which meshes with a gear 430 connected to the end of drive shaft 432 for outer cutter head 410. The outer cutter head 410 is thus driven by shaft 168 in a direction opposite to the direction of rotation of shaft 168. A similar gear train 434 and 436 drives an intermediate shaft 438 that, in turn, drives a pair of meshing gears 440 and 442. The gear 442 is connected to a shaft 444 so that rotation of gear 442 is transmitted through shaft 444 to a gear 446 nonrotatably connected to shaft 444. The outer cutter head 412 has a drive shaft 448 that has a gear 450 connected thereto and meshing with gear 446. With this arrangement the outer cutter head 412 is rotated by the shaft 168 in a direction opposite to the rotation of shaft 168. Thus, both outer cutter heads 410 and 412 are drivingly connected to each other to rotate in the same direction at substantially the same peripheral velocity.

The end portion of the gear train to drive outer cutter head 410 is illustrated in FIGURE 16 wherein the articulated drive shaft 432 is illustrated with an intermediate Rezeppe type universal joint 452. The Rezeppe type universal joint 452 provides a drive connection for the cutter heads, as has been previously described. The gears 430 and 428 are illustrated in meshing relation with each other in FIGURE 16 and diagrammatically illustrated in FIGURE 18 within the outer turntable housing generally designated by the numeral 454. The shaft 426 connected to gear 428 extends rearwardly from the outer turntable housing into the inner portion of the inner turntable housing generally designated 456. Within the inner turntable housing 456 the gear 424 splined to the rear end portion of shaft 426 meshes with gear 422 formed on shaft 420. The shaft 420 extends rearwardly into the turret body portion or main housing generally designated by the numeral 458. Gear 418 is secured to the end portion of shaft 420 within the turret body portion 458. The remaining gearing between drive shaft 168 and the gear 418 is not shown in FIGURE 16 but is similar to the gearing arrangement illustrated in FIGURE 6. The drive for the outer cutter heads 410 and 412 on turrets 402, 404 and 406 is similar to the drive previously described on turret 408.

Referring generally to FIGURES 13, 14 and 15, the general outer configuration of the turrets 402, 404, 406 and 408 is illustrated. The turrets are of substantially the same construction and shape, and have a main housing or body portion 458 that houses the shafting and gearing for driving all of the rotary cutter heads and the

center pilot drill. The body portion 458 has a forwardly extending support portion 460 for the intermediate cutter head 82 and the center pilot drill 86. The support portion 460 houses the drive gearing for the intermediate cutter head 82 and the center pilot drill 86.

Secured to the front portion of the housing 458 are a pair of inner turntable housings generally designated by the numeral 456 which are rotatable relative to the body portion 458. Secured to and supported by the inner turntable housings 456 are outer turntable housings generally designated 454. The outer turntable housings 454 are rotatable relative to the inner turntable housings 456 to provide a means for extending and retracting the outer cutter heads 410 and 412, as will be later described in detail. Fixedly secured to the front face of the outer turntable housing 454 are outer cutter head supports 462 that are so shaped that the outer cutter heads affixed thereto are positioned in angular relation to the longitudinal axis of the rotary turret as has been previously described. To retract the outer cutter heads 410 and 412 the inner turntable housings 456 and the outer turntable housings 454 are rotated in a counterclockwise manner relative to each other to thereby move the outer cutter heads 410 and 412 toward the center pilot drill 86. The counter rotation of the inner turntable housing 456 and outer turntable housing 454 maintains the desired angularity of the outer cutter heads 410 and 412 relative to the axis of the turret regardless of the relative radial dimension of the turrets.

Turntable arrangement

FIGURE 15 illustrates how the constant angularity is maintained between the outer cutter heads 410 and 412 and the longitudinal axis of the turret in the various adjusted positions. FIGURE 15 is a composite view of the mining machine with the turret 402 in a fully retracted position of minimum diameter and the turret 404 in a partially extended position. Turrets 406 and 408 are illustrated at a fully extended position for maximum diameter cutting. It should be noted that although the outer cutter heads are illustrated in the various stages of extension from a minimum cutting diameter to a maximum cutting diameter, the relative angularity of the outer cutter heads is the same in all adjusted positions. Maintaining the angularity of the outer cutter heads constant is accomplished by the timed counter rotation of the inner and outer turntable housings. In FIGURE 15 the outer turntable housing 454 on turret 402 is in a fully retracted position on the inner turntable housing 456 and the outer cutter head 410 is at a preselected angular deviation relative to the longitudinal axis of the turret 402. Turret 406 in FIGURE 15 is in a fully extended position where the inner turntable housing 456 has rotated 180° relative to the turret body portion 458 when compared with the position of the turntable housing 456 on turret 402. The outer turntable 454 on turret 406 is in the same position relative to the turret housing 458 as the outer turntable 454 on turret 402 so that the outer cutter heads 410 and 412 on both turrets 402 and 406 have the same angular relationship to the longitudinal axis of the respective turrets. In an intermediate position, such as is illustrated by turret 404 in FIGURE 15, the inner turntable housing 456 has rotated through approximately 90° when compared with the inner turntable housing of turret 402. The outer turntable housing 454 on turret 404 has rotated substantially the same number of degrees as the inner turntable so that the outer cutter heads 410 and 412 on turret 404 have the same angular relationship to the longitudinal axis of turret 404 as the outer cutter heads 410 and 412 on the remaining rotary turrets. It should be understood that FIGURE 15 is a composite view illustrating the relative adjusted positions of the outer cutter heads. In actual practice, the outer cutter heads on all of the rotary turrets would be adjusted to provide the same effective diameter of all the turrets.

Details of turntables

Referring to FIGURE 16 the specific construction of the inner turntable housing 456 and the outer turntable housing 454 is illustrated. The turret main body portion 458 has a pair of openings 464 in its front face and an intermediate wall 466. The inner turntable housing 456 is generally cylindrical in shape and has a body portion 468 of reduced diameter and a rear end portion 470 of reduced diameter. The inner turntable 456 is positioned within the opening 464 in the turret body portion 458 with the end portion 470 of reduced diameter supported by bearings 472 for rotation relative to the turret housing 458.

The inner turntable body portion 468 has an externally toothed portion 474 which forms an external geared portion thereon. The external geared portion 474 may be formed separately, as is illustrated in FIGURE 21, and suitably coupled to the turntable housing rear end portion 470 and turntable body portion 468. The inner turntable housing body portion 468 has an outwardly extending cylindrical portion 476 which is displaced laterally from the longitudinal axis of the inner turntable housing body portion 468. For clarity the longitudinal axis of the inner turntable housing 468 is indicated by the dash dot line in FIGURE 16 and the numeral 478. The inner turntable forwardly extending cylindrical portion 476 is displaced laterally from the axis 478 and has an axis indicated by the dash dot line and the numeral 480. The inner turntable body portion 468 houses the gearing for adjusting or rotating the inner and outer turntables relative to each other.

The outer turntable housing 454 has a body portion 482 that houses the drive gearing for the outer cutter head 410, and has a rearwardly extending annular housing 484 with a rearwardly extending concentric tubular portion 486. The outer turntable 484 is positioned over the outwardly extending cylindrical portion 476 of inner turntable 456 with suitable bearings 488 therebetween. The outer turntable tubular portion 486 extends into the cylindrical opening in outwardly extending cylindrical portion 476, into the inner turntable body portion 468. The outer turntable housing 454 is thus rotatably supported on the inner turntable housing 456. The outer turntable housing 454 has a first axis that is coaxial with the laterally displaced axis 480 of inner turntable 456 and a second axis that is laterally displaced relative to axis 480 and is indicated by the numeral 490 in FIGURE 16. Thus the outer turntable 454 rotates relative to inner turntable 456 about axis 480 and the axis 490 of outer turntable 454 revolves about the axis 480. The inner turntable housing 456 rotates about axis 478 to thereby revolve the axis 480 therearound. With this construction the counter rotation of inner housing 456 and outer turntable housing 454 maintains the same angular relationship of outer cutter head 410 to the longitudinal axis of the turret so that the turrets can be adjusted to dislodge material of different thicknesses.

Drive mechanism for turntables

A drive mechanism is provided for counter rotation of both of the turntable housings 454 and 456 and is diagrammatically illustrated in FIGURE 22 and schematically illustrated in perspective in FIGURE 21. Referring now to FIGURE 21, the main transmission housing 42 supports the cylindrical end portion 76 of the respective turrets in a manner similar to that previously described. The cylindrical end portion 76 has an internally toothed ring gear 246. A tubular shaft 242 extends through the end portion 76 and has a gear 244 nonrotatably secured thereto. The gear 244 is movable axially on the tubular shaft 242 to mesh with a gear 250 that is driven by servomotor 254. A double acting piston cylinder actuator 268 is connected by means of a lever 266 to gear 244 at 248. The double acting cylinder 268 is arranged to move gear 244 into engagement with the gear 246 to lock the

tubular shaft to the turret end portion 76 so that the tubular shaft 244 rotates with the turret end portion 76. In this position the inner and outer turntables remain locked in a preselected fixed position. The double acting cylinder 268 is arranged to disengage the gear 244 from gear 246 and engage gear 240 thereto. Rotation of motor 254 rotates shaft 242 through gearing 250 and 244. The shaft 242 extends into the rear portion of the turret body portion 458 and has a gear 256 secured thereto and rotatable therewith. The gear 256 meshes with a gear 258 on shaft 260. This construction is similar to the gear train illustrated in FIGURE 8.

Referring to FIGURES 16 and 21 the shaft 260 has a gear 500 secured thereto and rotatable therewith. The gear 500 meshes with the gear 474 that forms a part of the inner turntable housing 456. Thus, rotation of gear 500 rotates the inner turntable housing about the axis 478. Referring to FIGURE 16, the inner turntable body portion 468 has a front end wall 502 and an intermediate wall 504. The intermediate wall 504 has a central aperture 506 therethrough and an aperture 508 spaced laterally from the axis 478. The front end wall 502 has a central aperture 510 therethrough which is aligned with the aperture 506 in the intermediate wall 504 and an aperture 512 aligned with the aperture 508. A shaft 514 is supported in the intermediate and front wall apertures 508 and 512 respectively and has coaxially positioned thereon and rotatable relative thereto an elongated gear 516. Bearings 518 are positioned between the shaft 514 and gear 516 to permit the gear 516 to freely rotate on the shaft 514. A shaft 520 is supported in the aperture 506 of the inner turntable intermediate wall 504 in bearings 522 positioned in a socket 524 in gear 422. The gear 422 has its outer portion supported in gear 424 in the intermediate wall aperture 506. Thus, gear 422 is rotatable relative to shaft 520. The shaft 520 has a gear 526 formed thereon which meshes with a portion of gear 516 rotatably mounted on shaft 514. The shaft 520 is suitably supported in the inner turntable end wall aperture 510 and has an end portion 528 extending outwardly beyond the front end wall 502.

Keyed to the end of shaft 520 is an arm 530 which is fixedly secured to the turret body portion 458 as is clearly illustrated in FIGURE 21. With this arrangement, as the inner turntable housing 456 is rotated about axis 478 by gears 500 and 474, the gear 526 because of its connection to arm 530 remains stationary and fixed and gear 516 meshing with gear 526 revolves therearound and rotates about the coaxial shaft 514.

The outer turntable tubular portion 486 has a gear 532 secured thereto within the inner turntable housing body portion 468. The gear 532 connected to the outer turntable 454 meshes with the gear 516 within the inner turntable body portion 468 and the rotation of gear 516 about fixed gear 526 and on shaft 514 rotates gear 532 connected to the outer turntable housing 454 to rotate the outer turntable housing 454 in a direction opposite to the direction of rotation of the inner turntable 456 about the axis 480, and axis 490 revolves about axis 480.

In FIGURE 21 the relative direction of rotation of the respective gears and shafts is indicated to retract the outer cutter head 410. Thus, rotation of shaft 260 and gear 500 in a clockwise direction rotates the inner turntable housing 456 through gear 474 in a counterclockwise direction. The outer turntable housing 454 is rotated in a clockwise direction through gears 516 and 532 to thereby retract the outer cutter head 410 and maintain the same angularity between the longitudinal axis of the turret and the outer cutter head 410. With this arrangement by the actuation of the hydraulic motor 254 the effective radial dimension of the turrets can be quickly adjusted for the relative height of the seam of material being dislodged and the relative angularity of the outer cutter heads to the axis of the turrets maintained the same in all adjusted positions.

With the mining machine described, the angular relation of the outer cutter heads to the axis of the turret is maintained the same throughout all radial positions of the outer cutter head. There is also provided a pair of driven outer cutter heads that are both radially adjustable so that a greater number of driven or rotating cutter devices are available to more rapidly dislodge the material from the face.

Cutter head

FIGURES 25 and 26 illustrate in detail a cutter head generally designated by the numeral 662 that is similar to the cutter heads previously illustrated and generally described in conjunction with the rotatable turrets. The cutter head is rotatably supported on a cylindrical support member 664 and has an annular body portion 666, an annular front head portion 668 and a cap 670.

Seated on the front annular surface 672 of the cylindrical support member 664 is an annular bearing support member 674 that has a central passageway 676 therethrough and a pair of spaced shoulder portions 678 and 680 for bearings 682 and 684. A shaft 686 has an intermediate portion positioned in the axial passageway 676 of cylindrical support member 664 and rotatably supported by bearings 682 and 684. The shaft 686 has a radially extending and inturned flanged end portion 688 with an axial threaded bore 690 and a plurality of spaced threaded bores 692 that are spaced radially from the bore 690. The cutter head annular body portion 666 is splined to the shaft radially flanged end portion 688 for rotation therewith and has a plurality of passageways 694 arranged adjacent the peripheral edge. The passageways 694 have an enlarged portion 696 in which a cylindrical receiver 698 is positioned. The receiver terminates at the front surface of the annular body portion 666. A suitable seal 700 is positioned between the outer surface of the bearing support 674 and the inner surface of the annular body portion 666.

The cutter head annular front head portion 668 has a central bore 702 with an enlarged inner end forming a shoulder 704 and an enlarged outer end forming a shoulder 706. The rear surface of annular front head portion 668 has a plurality of cylindrical recessed portions 708 adjacent the peripheral edge with cylindrical receivers 710 positioned therein. The cylindrical recessed portions 708 are arranged circumferentially and aligned with the passageways 694 in the body portion 666. Shear pins 712 are positioned in the aligned passageways 694 and recessed portions 708 to secure the annular head portion 668 to the body portion 666. If during the cutting operation the bits encounter a resistance or opposition to rotation that exceeds the shear strength of the shear pins 712, the pins will shear or part along the central recessed portion 711 and permit the annular front head portion 668 to rotate freely relative to the body portion 666 and thus literally disconnect the annular front head portion 668 from the drive means for rotating the cutter heads 662. With this arrangement, the drive gearing is protected from damage due to excessive damaging loads or forces.

The annular front head portion 668 is maintained in position on the body portion 666 by the flanged cap member 670. The axial bolt 714 extends through aperture 716 in cap member 670 and into the threaded aperture 690 in shaft 686. Bolts 718 extend through receiving aperture 720 in cap 670 and into threaded apertures 692 in shaft 686 to thereby maintain the annular head portion 668 in overlying and axially aligned relation with body portion 666. The annular front head portion 668 has an irregular convex front surface or front cutting face 722 in which bit receivers 724 are positioned. Cutter bits 725 are secured in the bit receivers 724 and extend generally forwardly from the front cutting face 722. The front surface 722 is sloped so that the bits 724 extend forwardly from the cutter head at an acute angle to the longitudinal axis of the cutter head.

The front surface 722 has raised bit receiving surfaces 726 and alternate recessed bit receiving surfaces 728. FIGURE 26 is taken along the line 26—26 in FIGURE 25 and the upper bit 725 in FIGURE 26 is positioned in a bit receiver 724 on the elevated bit receiving surface 726 and the bit 725 illustrated at the lower portion of FIGURE 26 is in a recessed bit receiving portion 728. The raised bit receiving portions 726 are sloped and so arranged that the longitudinal axis of the bit is at a 45° angle with the longitudinal axis of the cutter head 662. The lower recessed portions 728 are sloped at a different angle so that the longitudinal axis of the bit is at an angle of 30° with the longitudinal axis of the cutter head 662. The bit receivers 724 are positioned in elevated bit receiving portions 726 in a manner that the rectangular bit receiving recesses 730 are arranged in a circular configuration about the axis of the cutter head. The rectangular recesses 730 have a transverse axis deviating about 15° from an axis generated radially as is illustrated in FIGURE 25. Similarly, the recessed bit receiving surfaces 732 have bit receivers 724 positioned therein so that the rectangular bit receiving apertures 732 are also arranged equidistantly from the axis of the cutter head and have their transverse axis at an angle of about 15°.

20 The shaft 686 is connected to the drive gearing as previously described to rotate the cutter head 662 relative to the tubular member 664. The cutter bits 725 are arranged upon rotation to dislodge material from the face as is described in U.S. Patent Re. 25,470. If the bits 725 encounter a resistance to rotation that exceeds the shear strength of the shear pins 712, the shear pins 712 break or shear along the recessed portion 711 and disconnect the cutter head front head portion 668 from the body portion 666 to relieve the stresses on the drive 30 gearing. Although the various angular relationships between the components of the cutter head and the drill bits positioned thereon provide an efficient cutter head, it should be understood that these angular relationships are stated for exemplary purposes only, and it is not intended to confine the hereinabove described invention to these particular angular relationships.

35 While there is in this application specifically disclosed two forms which the invention may assume in practice, it will be understood that these forms are shown for purposes of illustration and that the invention may be modified and embodied in various other forms without departing from its spirit or the scope of the appended claims.

40 According to the provisions of the patent statutes, the principle, preferred construction and mode of operation of the invention have been explained and what is considered to represent its best embodiments have been illustrated and described. However, it should be understood that within the scope of the appended claims, the invention may be practiced otherwise than as specifically illustrated and described.

We claim:

1. A rotatable turret comprising,
a body portion having a longitudinal axis about which said body portion rotates,
a cutter head rotatably supported on the front end of said body portion in angular relation to and spaced laterally from said body portion longitudinal axis, said cutter head having an axis of rotation in angular relation with said body portion longitudinal axis,
said cutter head having a plurality of cutting devices secured thereto and extending from the front portion of said cutter head, said cutting devices having cutting edges facing in the direction of rotation of said cutter head,
drive means within said body portion to rotate said cutter head about said cutter head axis of rotation, and
adjusting means to move said cutter head radially rel-

- ative to the longitudinal axis of said body portion and maintain said angular relation between said cutter head and said body portion longitudinal axis.
2. A rotatable turret comprising,
a body portion having a longitudinal axis about which said body portion rotates,
a cutter head support means mounted on the front end of said body portion in spaced lateral relation to said body portion longitudinal axis,
a cutter head rotatably secured to the front end portion of said cutter head support means and having a front portion and an axis of rotation,
a plurality of cutting devices secured to and extending from said cutter head front portion,
said cutting devices having cutting edges facing the direction of rotation of said cutter head,
said cutter head axis of rotation inclined in the direction of rotation of said body portion and diverging outwardly relative to said body portion longitudinal axis to thereby position said cutter head front portion in a preselected angular relation to said body portion longitudinal axis, and
means to rotate said cutter head support means about an axis parallel to and laterally spaced from said body portion longitudinal axis to move said cutter head toward and away from said body portion longitudinal axis and change the angular relation of said cutter head front portion to said body portion longitudinal axis.
3. A rotatable turret comprising,
a body portion having a longitudinal axis about which said body portion rotates,
a cutter head support means mounted on the front of said body portion in spaced lateral relation to said body portion longitudinal axis,
said cutter head support means including a first turntable portion and a second turntable portion, said first turntable portion being rotatable about a first axis parallel to and spaced laterally from said body portion longitudinal axis,
said second turntable portion being rotatable about a second axis parallel to and spaced laterally from said first axis,
a cutter head rotatably secured to the front end portion of said cutter head support means and having a front portion and an axis of rotation,
a plurality of cutting devices secured to and extending from said cutter head front portion, said cutting devices having cutting edges facing the direction of rotation of said cutter head,
said cutter head axis of rotation inclined in the direction of rotation of said body portion and diverging outwardly relative to said body portion longitudinal axis to thereby position said cutter head front portion in a preselected angular relation to said body portion longitudinal axis, and
means to rotate said first turntable about said first axis to move said cutter head toward and away from said body portion longitudinal axis and to rotate said second turntable about said second axis to change the angular relation of said cutter head front portion to said body portion longitudinal axis.
4. A rotatable turret comprising,
a body portion having a longitudinal axis about which said body portion rotates,
an intermediate cutter head rotatably supported on the front end of said body portion in angular relation to and spaced laterally from said body portion longitudinal axis a first preselected distance,
an outer cutter head rotatably supported on the front end of said body portion in angular relation to and spaced laterally from said body portion longitudinal axis a second preselected distance greater than said first preselected distance of said intermediate cutter head,

- a plurality of cutting devices secured to and extending from the front portion of said cutter heads, said cutting devices having cutting edges facing the direction of rotation of said respective cutter head, drive means within said body portion to rotate said cutter heads in the same direction, and
means to move said outer cutter head radially relative to the longitudinal axis of said body portion and change the angular relation of said outer cutter head to said body portion longitudinal axis.
5. A rotatable turret comprising,
a body portion having a longitudinal axis about which said body portion rotates,
an intermediate cutter head rotatably supported on the front end of said body portion in angular relation to and spaced laterally from said body portion longitudinal axis,
an outer cutter head support means mounted on the front end of said body portion in spaced lateral relation to said body portion longitudinal axis,
said outer cutter head support means including a first turntable portion and a second turntable portion, said first turntable portion being rotatable about a first axis parallel to and spaced laterally from said body portion longitudinal axis, said second turntable portion being rotatable about a second axis parallel to and spaced laterally from said first axis,
an outer cutter head rotatably secured to the front end portion of said outer cutter head support means, said intermediate and outer cutter heads having a front portion and an axis of rotation,
a plurality of cutting devices secured to and extending from the front portion of said cutter heads, said cutting devices having cutting edges facing the direction of rotation of said respective cutter head, drive means within said body portion to rotate said cutter heads in the same direction, and
means to rotate said first turntable about said first axis to move said outer cutter head toward and away from said body portion longitudinal axis and to rotate said second turntable about said second axis to change the angular relation of said outer cutter head front portion to said body portion longitudinal axis.
6. A rotatable turret as set forth in claim 5 in which said first turntable has an externally toothed gear portion within said body portion,
a shaft rotatably supported in said body portion and having a gear secured thereto and in meshing with said externally toothed gear portion on said first turntable, and
means to rotate said shaft and thereby rotate said first turntable about said first axis to move said cutter head toward and away from said body portion longitudinal axis.
7. A rotatable turret as set forth in claim 5 in which said first turntable has an externally toothed gear portion within said body portion,
a shaft rotatably supported in said body portion and having a gear secured thereto and meshing with said externally toothed gear portion on said first turntable, and
means to nonrotatably connect said shaft to said body portion so that said shaft rotates with said body portion and through said gear maintains said first turntable in fixed relation to said body portion.
8. A rotatable turret comprising,
a body portion having a longitudinal axis about which said body portion rotates,
cutter head support means mounted on the front of said body portion in spaced lateral relation to said body portion longitudinal axis,
said cutter head support means including a first turntable portion and a second turntable portion, said first turntable portion being rotatable about a first

axis parallel to and spaced laterally from said body portion longitudinal axis, said second turntable portion being rotatable about a second axis parallel to and spaced laterally from said first axis, a cutter head rotatably secured to the front end portion of said second turntable portion and having a front portion and an axis of rotation, a plurality of cutting devices secured to and extending from said cutter head front portion, said cutting devices having cutting edges facing the direction of rotation of said cutter head, said cutter head axis of rotation inclined in the direction of rotation of said body portion and diverging outwardly relative to said body portion longitudinal axis to thereby position said cutter head front portion in a preselected angular relation to said body portion longitudinal axis, said first turntable having an externally toothed gear portion within said body portion, a shaft rotatably supported in said body portion and having a gear secured thereto and in meshing relation with said externally toothed gear portion on said first turntable, means to rotate said shaft and thereby rotate said first turntable about said first axis to move said cutter head toward and away from said body portion longitudinal axis, and means to secure said second turntable to said first turntable at different adjusted positions of said second turntable to thereby maintain a preselected angular relation of said cutter head front portion to said body portion longitudinal axis at various adjusted positions of said first turntable.

9. A rotatable turntable as set forth in claim 8 in which said locking means includes an arcuate portion on the front surface of said first turntable with a plurality of slotted portions therein, said second turntable having a portion extending laterally from said second axis and in overlying relation with said arcuate portion on said first turntable front surface, said laterally extending portion of said second turntable having a slotted portion therein in overlying relation with said arcuate portion, and means positioned in one of said first turntable slotted portions and in said second turntable slotted portion to nonrotatably secure said second turntable to said first turntable.

10. A rotatable turret as set forth in claim 8 which includes, a first drive shaft positioned in said body portion and extending into said first turntable portion in coaxial relation with said first turntable first axis, a second drive shaft positioned in said first turntable portion and extending into said second turntable portion in coaxial relation with said second turntable second axis, gear means in said first turntable drivingly connecting said first shaft and said second shaft, drive means to rotate said first shaft, and universal means connecting said second drive shaft to said cutter head to rotate said cutter head in said preselected angular relation to said body portion longitudinal axis.

11. A rotatable turret comprising, a body portion having a longitudinal axis about which said body portion rotates, a pilot drill rotatably supported on the front end of said body portion in coaxial relation with said body portion longitudinal axis, an intermediate cutter head rotatably supported on the front end of said body portion in angular relation to and spaced laterally from said body portion longitudinal axis at a first preselected distance,

an outer cutter head support means mounted on the front end of said body portion in lateral spaced relation to said body portion longitudinal axis, said center pilot drill positioned between said intermediate cutter head and said outer cutter head support means, said outer cutter head support means including a first turntable portion and a second turntable portion, said first turntable portion being rotatable about a first axis parallel to and spaced laterally from said body portion longitudinal axis, said second turntable portion being rotatable about a second axis parallel to and spaced laterally from said first axis, an outer cutter head rotatably secured to the front end portion of said second turntable portion, said intermediate and outer cutter heads having a front portion and an axis of rotation, said axes of rotation of both said intermediate cutter head and said outer cutter head being inclined in the direction of rotation of said body portion and diverging outwardly relative to said body portion longitudinal axis so that the front portion of both said intermediate cutter head and said outer cutter head are in the same preselected angular relation to said body portion longitudinal axis, a main drive shaft rotatably positioned in said body portion in coaxial relation with said body portion longitudinal axis, an intermediate cutter head drive shaft rotatably supported in said body portion and having an end portion drivingly connected to said intermediate cutter head, a first outer cutter head drive shaft positioned in said body portion in parallel laterally spaced relation to said main drive shaft and having an end portion extending into said first turntable portion, a second outer cutter head drive shaft positioned in said first turntable portion in spaced parallel relation to said first outer cutter head drive shaft, universal means connecting said second outer cutter head drive shaft to said outer cutter head, gear means within said first turntable portion connecting said first outer cutter head drive shaft to said second outer cutter head drive shaft, a center pilot drill drive shaft positioned within said body portion and connected to said center pilot drill, gear means within said body portion connecting said intermediate cutter head drive shaft and said center pilot drill drive shaft, other gear means in said body portion connecting said main drive shaft to said intermediate cutter head drive shaft and said outer cutter head first drive shaft to rotate said intermediate cutter head and said outer cutter head in the same direction upon rotation of said main drive shaft, and means to rotate said first and second turntable portions relative to each other to move said outer cutter head toward and away from said center pilot drill and maintain the same preselected angular relation between said outer cutter head front face and said body portion longitudinal axis.

12. A rotatable turret comprising a body portion having a longitudinal axis about which said body portion rotates, a cutter head support means mounted on the front end of said body portion in spaced lateral relation to said body portion longitudinal axis, said cutter head support means including a first turntable portion and a second turntable portion, said first turntable portion being rotatable about a first axis parallel to and spaced laterally from said body portion longitudinal axis, said second turntable portion being rotatable about a second axis parallel to and spaced laterally from said first axis,

a cutter head rotatably secured to the front end portion of said cutter head support means and having a front portion and an axis of rotation, a plurality of cutting devices secured to and extending from said cutter head front portion, said cutting devices having cutting edges facing the direction of rotation of said cutter head, 5 said cutter head axis of rotation inclined in the direction of rotation of said body portion and diverging outwardly relative to said body portion longitudinal axis to thereby position said cutter head front face in a preselected angular relation to said body portion longitudinal axis, and means to concurrently rotate both of said turntables about said respective axes to move said cutter head toward and away from said body portion longitudinal axis and to maintain said angular relation between said cutter head front portion and said body portion longitudinal axis substantially constant. 10 15

13. A rotatable turret as set forth in claim 12 in which said means to concurrently rotate both of said turntables comprises, said first turntable having an intermediate wall and a front wall, 20 a first shaft fixedly secured in said first turntable front wall and intermediate wall in coaxial relation with said first turntable first axis, a first gear coaxially positioned on and nonrotatably secured to said first shaft, 25 a second shaft supported in said first turntable front wall and intermediate wall in parallel spaced relation to said first shaft, a second gear coaxially positioned on said second shaft in rotatable relation thereto, said second gear meshing with said first gear, 30 a second turntable having an end portion extending into said first turntable portion and having an externally toothed gear portion thereon, said second turntable externally toothed gear portion meshing with said second gear, 35 said second turntable having an end portion extending into said first turntable portion and having an externally toothed gear portion thereon, said second turntable externally toothed gear portion meshing with said second gear, and means to rotate said first turntable about said first axis in a given direction to thereby revolve said second gear about said first turntable axis and rotate said second gear on said second shaft and thereby rotate said second turntable in an opposite direction to thereby move said cutter head radially relative to said body portion longitudinal axis and maintain the angular relation between said cutter head front portion and said body portion longitudinal axis substantially constant. 40 45

14. A rotatable turret as set forth in claim 13 which includes,

an externally geared portion on said first turntable within said body portion, an adjusting shaft rotatably supported in said body portion, 50 gearing connecting said adjusting shaft and said first turntable externally geared portion, means to rotate said adjusting shaft and thereby adjust the relative radial position of said outer cutter head, and means to connect said shaft to said body portion and thereby lock said turntables in a fixed position on said body portion. 60

15. A rotatable turret comprising,

a body portion having a longitudinal axis about which said body portion rotates, an intermediate cutter head rotatably supported on the front end of said body portion in angular relation to and spaced laterally from said body portion longitudinal axis a first preselected distance, 70 a pair of outer cutter heads rotatably supported on the front end of said body portion in angular relation to and spaced laterally from said body portion 75

longitudinal axis a second preselected distance greater than said first preselected distance of said intermediate cutter head and on opposite sides of said body portion longitudinal axis,

a plurality of cutting devices secured to and extending from the front portion of said cutter heads, said cutting devices having cutting edges facing the direction of rotation of said respective cutter head, drive means within said body portion to rotate said intermediate cutter head and said pair of outer cutter heads in the same direction, and means to move said outer cutter heads radially relative to the longitudinal axis of said body portion and change said angular relation between said outer cutter heads and said body portion longitudinal axis. 10 15

16. In a continuous mining machine the combination comprising,

a main frame, a plurality of turrets rotatably supported on the front end of said main frame in parallel spaced relation to each other, said turrets each having an axis of rotation, said turrets each having a plurality of rotary cutter heads spaced laterally from said turret axis of rotation and extending forwardly therefrom, said cutter heads each having an axis of rotation arranged in a preselected angular relation to said respective turret axis of rotation, said cutter heads having cutting devices extending forwardly therefrom, said cutter heads arranged to rotate about said cutter head axis of rotation and revolve about said turret axis of rotation, means to revolve certain of said cutter heads about an axis spaced from said turret axis of rotation to thereby move said respective cutter heads laterally relative to said respective turret axis of rotation, and means to rotate said turrets about their respective axes of rotation in timed relation to each other and to rotate said cutter heads on each of said turrets about their axes of rotation. 20 25 30 35 40 45

17. A continuous mining machine as set forth in claim 16 which includes,

a pilot drill extending forwardly from each of said turrets and arranged coaxially with said respective turret axis of rotation, and means to rotate said pilot drills at an angular velocity greater than the angular velocity of the respective turrets. 50

18. A continuous mining machine as set forth in claim 16 in which said means to rotate said turrets and said cutter heads includes,

a main transmission having constantly meshing gearing, shafting connected to certain of said gearing and rotatably driven thereby, other gearing within said turrets connecting said shafting to said cutter heads to thereby rotate said cutter heads about said respective cutter head axes of rotation, other shafting connected to other of said gearing in said main transmission and rotatably driven thereby, and

70 turret drive gearing connecting said other shafting to said turrets to thereby rotate said turrets about said respective turret axes of rotation.

19. In a continuous mining machine the combination comprising,

a main frame, a plurality of turrets rotatably supported on the front end of said main frame in parallel spaced relation to each other, said turrets each having an axis of rotation, said turrets each having an intermediate cutter head

and an outer cutter head extending forwardly therefrom in spaced lateral relation to and on opposite sides of said turret axis of rotation,
 5 said intermediate and outer cutter heads having an axis of rotation arranged in a preselected angular relation to said respective turret axis of rotation, said cutter heads having cutting devices extending forwardly therefrom, said intermediate and outer cutter heads arranged to rotate about said cutter head axis of rotation and revolve about said turret axis of rotation,
 10 said intermediate cutter head secured to said respective turret in fixed lateral spaced relation to said respective turret axis of rotation, said outer cutter heads being movable laterally relative to said turret axis of rotation,
 15 said turrets having means to adjust the angular relation between said outer cutter head axis of rotation and said respective turret axis of rotation, and means to rotate said turret about their respective axes 20 of rotation in timed relation to each other and to rotate said cutter heads on each of said turrets about their axes of rotation at a different angular velocity than the angular velocity of said turrets.

20. In a continuous mining machine the combination comprising,
 a main frame,
 a plurality of turrets rotatably supported on the front end of said main frame in parallel spaced relation to each other,
 25 said turrets each having an axis of rotation, said turrets each having an intermediate cutter head and a pair of outer cutter heads extending forwardly therefrom, said outer cutter heads arranged on opposite sides of said turret axis of rotation, said intermediate and outer cutter heads having an axis of rotation arranged in a preselected angular relation to said respective turret axis of rotation, said cutter heads having cutting devices extending forwardly therefrom, said intermediate and outer cutter heads arranged to rotate about said cutter head axis of rotation and revolve about said turret axis of rotation,
 30 said intermediate cutter head secured to said respective turret in fixed lateral spaced relation to said respective turret axis of rotation, said outer cutter heads being movable laterally relative to said turret axis of rotation,
 35 said turrets having means to adjust the angular relation between said axis of rotation of said pairs of outer cutter heads and said respective turret axis of rotation, and means to rotate said turrets about their respective axes of rotation in timed relation to each other and to rotate said cutter heads on each of said turrets about their axes of rotation in a direction opposite to the direction of rotation of said respective turret.
 40

21. In a continuous mining machine the combination comprising,
 a main frame,
 a plurality of turrets rotatably supported on the front end of said main frame in parallel spaced relation to each other,
 45 said turrets each having an axis of rotation, said turrets each having a pilot drill extending forwardly therefrom and coaxially with said respective turret axis of rotation, said turrets each having a plurality of rotary cutter heads extending forwardly therefrom in spaced lateral relation to said turret axis of rotation, said cutter heads having an axis of rotation arranged in a preselected angular relation to said respective turret axis of rotation, said cutter heads arranged to rotate about said cutter head axis of rotation and revolve about said turret axis of rotation,
 50

said pilot drills arranged to rotate on said turret axis of rotation,
 means to adjust certain of said cutter heads laterally relative to said turret axis of rotation, and interconnected means to rotate said turrets about their respective axis of rotation in timed relation to each other and rotate said cutter heads and pilot drills on each of said turrets about their respective axes of rotation at a different angular velocity than the angular velocity of said turrets, said cutter heads on each of said turrets arranged to rotate in a direction opposite to the direction of rotation of said respective turret.

22. A continuous mining machine as set forth in claim 21 in which,
 said main frame includes a longitudinally extending trough shaped conveyor compartment with a front opening adjacent said turrets, endless conveyor means in said compartment arranged to convey dislodged material rearwardly therethrough, said turrets having paddle portions extending laterally therefrom and rotatable therewith, said paddle portions arranged to direct dislodged material laterally toward said conveyor compartment front opening.

23. In a continuous mining machine the combination comprising,
 a main frame having a centrally positioned trough shaped conveyor compartment extending longitudinally therethrough and having a front opening, endless conveyor means in said compartment arranged to convey dislodged material rearwardly therethrough,
 35 two pairs of turrets rotatably supported on the front end of said main frame in parallel spaced relation to each other and on opposite sides of said conveyor compartment front opening, said turrets each having an axis of rotation, said turrets each having a plurality of rotary cutter heads spaced laterally from said turret axis of rotation and extending forwardly therefrom, said cutter heads each having an axis of rotation arranged in a preselected angular relation to said respective turret axis of rotation, said cutter heads having cutting devices extending forwardly therefrom, said cutter heads arranged to rotate about said cutter head axis of rotation and revolve about said turret axis of rotation, means to move certain of said cutter heads laterally relative to said turret axis of rotation, and interconnected means to rotate said pairs of turrets in opposite directions and in timed relation to each other and to rotate said cutter heads on each of said turrets about their respective axes of rotation at a different angular velocity than the angular velocity of said turrets, said cutter heads on each of said turrets arranged to rotate in a direction opposite to the direction of rotation of said respective turret.

24. A continuous mining machine as set forth in claim 23 in which,
 said pairs of turrets rotate in a direction toward the center of said main frame, each of said turrets having paddle portions extending laterally therefrom and rotatable therewith, said paddle portions arranged to direct said dislodged material toward said conveyor compartment front opening.

25. A continuous mining machine as set forth in claim 23 in which,
 each of said turrets have paddle portions extending laterally therefrom and rotatable therewith, said paddle portions on the outer pair of said turrets arranged to move dislodged material forwardly away from said frame,

said paddles on the inner pair of said turrets arranged to move dislodged material toward the center of said main frame.

26. A continuous mining machine as set forth in claim 23 in which, said means to move certain of said cutter heads laterally relative to said turret axis of rotation includes pairs of turntables arranged in overlying relation with each other, and means to rotate said pairs of turntables in opposite directions to maintain said preselected angular relation between said turret axis of rotation and said cutter head axis of rotation.
